UNITED STATES PATENT OFFICE.

WILLIAM ALLEN CAMP, OF HARTFORD, CONNECTICUT.

TOY.

1,412,448.

Specification of Letters Patent. Patented Apr. 11, 1922.

Application filed November 25, 1919. Serial No. 340,614.

To all whom it may concern:

Be it known that I, WILLIAM A. CAMP, a citizen of the United States, residing at Hartford, in the county of Hartford, State of Connecticut, have invented certain new and useful Improvements in a Toy, of which the following is a specification.

The object of the present invention is to provide an improved toy wherein a block representing a figure will gravitate in a series of partial revolutions of somersaults down a series of vertically spaced horizontally disposed bars.

In the accompanying drawings:—

Fig. 1 is an elevational view of the toy.

Fig. 2 is a vertical sectional view through the ladder thereof.

Fig. 3 is a perspective view of the tumbling block, and

Fig. 4 is a view of a blank from which the block may be formed.

In these drawings; 10 designates horizontal bars which, in the present illustrative disclosure of the invention, form the rungs 25 of a ladder A maintained perpendicularly in any suitable manner as by means of the bases shown. The bars or rungs 10 are preferably rectangular in cross section being of considerably greater height than width.

30 The tumbling block 11, which may represent a figure or manikin of any kind and herein shown as bearing the representation of a clown, has at each end a transverse V-shaped groove 12, a circular hole 13 spaced 35 from the groove 12 and a narrow slot or channel 14 leading from the apex of the groove to the hole. Channels 14 are of slightly greater width than that of the rungs 10 but less than the height thereof.

40 It is of course evident that tumbling blocks may be solid and provided at each end with a groove, a channel and a hole arranged as described, but because of economy in manufacture, these blocks are by preference formed from sheet metal, a blank of the configuration shown in Fig. 4 being stamped from the metal and then bent along the dotted lines of this figure into rectangular shape as shown in Fig. 3.

50 In Fig. 2 of the drawings, the block shown in full lines is swinging downwardly about one of the upper rungs of the ladder; the first block shown in dotted lines as just falling from that rung onto the next succeeding rung; and the second block shown in dotted

lines is just dropping from a rung about which the block has swung. It will readily be understood that in operation the block is moved vertically down until the upper rung is positioned within the hole in the lower end 60 of the block and the block is then released whereupon it will swing downwardly until it is vertically below the rung about which it has swung and in this position the channel 14 and the rung 10 are in alinement so that 65 the block may fall from that rung and onto the next succeeding rung about which it will swing until it is vertically beneath the same when it will drop on to the next rung and so on. As the width of the channels is slightly 70 greater than that of the bars or rungs 10 it necessarily follows that the block must fall substantially on a perpendicular line from one rung to another. The inclined faces of the transverse grooves 12 are of 75 assistance in directing the block as it drops onto the rungs.

It is to be understood that the present disclosure of the invention is by way of illustration and not restrictive thereof, it being 80 obvious that the invention is susceptible of embodiment in various forms all coming within the scope of the following claims:

I claim as my invention:

1. In a toy, a series of vertically spaced 85 horizontally disposed bars, and a block having adjacent each end a transverse hole and a slot leading from each hole to the respective ends of the block.

2. In a toy, a series of vertically spaced 90 horizontally disposed bars, and a block having a transverse hole adjacent each end and a narrow channel leading from each hole to the respective ends of the block.

3. In a toy, a series of vertically spaced 95 horizontally disposed bars of greater height than width, and a block having a transverse hole adjacent each end and a channel leading from each hole to the respective ends of the block, said channels being in width 100 less than the height but greater than the width of said bars.

4. In a toy, a series of vertically spaced horizontally disposed bars, and a block having 105 at each end a transverse V-shaped groove, a hole spaced from each groove, and a channel between the apex of each groove and the hole adjacent thereto.

5. In a toy, a vertical ladder having rungs of greater height than width, and a block 110

representing a figure and having at each end a transverse V-shaped groove, a hole spaced from each groove and a slot connecting the groove and hole at each end of the block, the width of each slot being less than the height of the rungs but slightly greater than the width thereof.

6. A hollow tumbling block formed from a blank of sheet metal, and having a pair 10 of opposite walls each provided at each end

with a groove, a hole spaced therefrom and a channel between the groove and hole.

7. In a toy, a series of bars spaced one above the other and a block including means at each end receiving said bars on dropping 15 thereonto and released from said bars when in position beneath the same whereby said block will tumble down said bars in a series of partial revolutions.

WILLIAM ALLEN CAMP.
